UNITED STATES PATENT OFFICE.

ALFRED T. FOWLES, OF DALLAS, TEXAS.

WATER-HEATER.

1,382,495.

Specification of Letters Patent. Patented June 21, 1921.

Application filed June 13, 1919. Serial No. 304,041.

To all whom it may concern:

Be it known that I, ALFRED T. FOWLES, a citizen of the United States, residing at Dallas, in the county of Dallas and State of Texas, have invented certain new and useful Improvements in Water-Heaters, of which the following is a specification.

This invention has for its object to provide an improved and simplified water heater especially designed for application to standard types of boilers whereby the latter is utilized as a reservoir for receiving the heated water from the heating apparatus.

Another object is the provision of a water heater of this character embodying a novel type of two-part jacket or casing conveniently applicable to the lower portion of conventional types of boilers and forming a passage causing the circulation of heat and the products of combustion from the burner about a portion of the boiler thereby materially assisting in the heating operation and providing for maximum utilization of the fuel expended.

With these and other objects in view as will appear as the description proceeds the invention comprises the novel features of construction, combination of elements and arrangements of parts which will be more fully described in the following specification and set forth with particularity in the claims appended hereto.

Figure 1 represents a front elevation of a conventional type of boiler, partly in section illustrating the invention applied thereto.

Fig. 2 represents a horizontal sectional view on the line 2—2 of Fig. 1.

Fig. 3 represents a perspective view of the boiler supporting ring removed from the stand.

Fig. 4 represents a perspective view of one of the parts of the boiler jacket or casing.

Fig. 5 represents a perspective view of the outlet pipe or flue.

Referring to the drawings in detail, wherein similar reference characters designate corresponding parts throughout the several views the numeral 5 indicates a well known type of boiler stand or support carrying a circular rim 6 at its upper terminal of approximately the same diameter as the lower flanged portion of the boiler 7 which the stand is designed to support. Ordinarily the boiler is supported directly upon the

rim 6, however in applying my invention to use I provide a supplementary supporting element designated by the numeral 8 which is substantially in the form of a ring 60 being provided at its upper portion with a groove provided with internal transverse ribs 9 upon which the lower flanged terminal of the boiler 7 is supported and which provides, between the ribs, a series of radial 65 air passages permitting free circulation of air between the boiler and the walls of the groove. The lower portion of the ring is provided with a depending flange 10 having a serpentine lower edge resting upon the 70 rim 6 of the stand. The prominent portions of the irregular edge 11 engaging the rim 6 provide a series of openings constituting air passages for the heated air and products of combustion arising from the burner, to be 75 hereinafter more fully described.

A jacket or casing consisting of two separable and substantially semi-cylindrical sections 11 and 12 are assembled in proper relation about the lower portion of the boiler 80 7 and extend a distance below the lower terminal of the latter providing a depending apron constituting an inclosure for the burner which is located directly beneath the lower portion of the boiler 7. Each part of 85 the jacket is provided with a double metallic wall spaced apart to provide an internal chamber for the reception of an asbestos or other non-heat conducting lining 13 and the opposed vertical edges of one 90 section are provided with pivoted hooks 14 or equivalent fastening devices engageable with lugs or keepers 15 on the other section whereby the sections are retained in properly assembled position about the boiler 95 structure 7. The upper portions of the two semi-cylindrical sections 11 and 12 are restricted in diameter as indicated at 16 so as to snugly fit about the boiler 7 and prevent the escape of the products of combustion from the chamber located between the exterior wall of the boiler 7 and the jacket and an ornamental two-part ring 17 is separably seated upon the upper restricted terminal of the jacket to maintain the latter in 100 105 predetermined position upon the boiler.

A hollow heating drum 18 is located directly beneath the boiler 7 and is connected with the lower portion thereof by a water inlet or supply pipe 19 which is preferably 110 connected with the heating drum at a point adjacent the center of the latter whereas the

water outlet pipe 20 having connection with the upper portion of the boiler 7 and with the hot water supply pipe 21 is connected with the side portion of the drum 18.

5 The lower portion of the heating drum 18 is connected with a drain pipe 22 having a valve 23 connected with the terminal portion thereof to facilitate cleansing and drainage of the boiler 7. A preferred type of gaseous 10 fuel burner 24 is located directly beneath the drum 18 and is so arranged that the flame therefrom is directed upon the outer surface of the drum. The burner 24 is supplied with fuel by a valved supply pipe 25.

15 A series of baffle plates 26 which are substantially V-shaped in cross section are secured at their web portions to the inner surfaces of the jacket sections 11 and 12 and the inner edges of the plates lie in contact 20 with the outer surface of the boiler 7. The plates 26 are arranged at uniformly spaced intervals within the jacket in such manner as to provide a series of vertical passages through which the heated air and products 25 of combustion arising from the burner 24 are conducted. A vertical flue 27 is arranged in the space between the jacket section 11 and the boiler 7 and is provided at its lower terminal with baffle flanges 28 which extend transversely between and close the passage between two of the adjacent register baffles 26. The lower portion of the flue is provided in its opposed side walls with inlet openings 29 through which the products of combustion 35 enter the flue after being caused to travel downwardly between the flue and the two adjacent baffles 26. The upper portion of the flue 27 is provided with a laterally extending hollow extension 30 which extends exteriorly of the jacket section 11 and is designed for connection with a flue pipe or other device for conducting the products of combustion from the water heater.

Owing to the sectional structure of the 45 jacket the heater may be conveniently applied to substantially any type of vertical boiler 7 and by interposing the ring 8 between the lower edge of the boiler and the stand rim 6 free circulation of air between 50 the boiler and the stand is afforded.

It is also evident that only slight modification in the structure of the conventional types of boilers is necessary to adapt the invention to use thereon as nearly all types of 55 boilers are provided with the usual drain pipe having connection with the lower portion thereof and this pipe is utilized by the applicant to form a connection between the lower portion of the boiler and the heating 60 drum 18, the pipe 20 being applied to con-

duct the heated water back to the top of the boiler or through the hot water supply pipe 21. The arrangement of the baffles 26 and at the openings 29 in the flue 27 insures a fair circulation of the products of combustion 65 about the lower portion of the boiler thereby accelerating the heating action of the contents thereof and utilizing such products of combustion directly heating the water contained within the boiler preliminary to its 70 admission to the heating drum 18.

What I claim is:

1. In an attachment for boilers comprising a removable sectional jacket seated about the lower section of a hot water boiler, a 75 series of vertical, equally spaced V-shaped baffle plates arranged internally of the jacket and maintaining the latter in spaced relation to the wall of the boiler and providing a plurality of vertical passages for directing 80 the air currents within said jacket, a flue extending vertically within the jacket having inlet ports in the lower portion thereof for receiving the products of combustion within the jacket and an outlet opening in 85 the upper portion of said flue arranged exteriorly of the jacket, said flue being disposed in spaced relation to the baffle plates.

2. In an attachment for a hot water boiler, comprising a two-part cylindrical jacket 90 adapted for application to a boiler and provided with a restricted upper terminal adapted to snugly fit the boiler, a plurality of baffle plates arranged in the jacket and terminating below the upper restricted terminal 95 thereof, a flue arranged internally of the jacket provided at its lower end with an inlet opening and in its upper terminal with an outlet opening arranged exteriorly of the jacket, a horizontal baffle connected with 100 the lower portion of the flue below the inlet opening and extending between two adjacent of the first mentioned baffles.

3. In a hot water heater, a jacket adapted for application to a boiler, a plurality of 105 vertical baffle plates arranged internally of the jacket, a vertically disposed flue extending centrally between two of the adjacent vertical baffle plates and having inlet openings in the opposed portions of the lower 110 terminal thereof and having an outlet port in the upper portion thereof arranged exteriorly of the jacket, and a horizontally disposed baffle carried by the flue disposed below the inlet openings and extending between the two adjacent vertical baffle plates.

In testimony whereof, I affix my signature hereto.

ALFRED T. FOWLES.
